UNITED STATES PATENT OFFICE

116,941

DESIGN FOR AN ARTIFICIAL HORIZON

William H. Van Gaasbeek, East Orange, N. J.

Application April 12, 1939, Serial No. 84,241

Term of patent 7 years

To all whom it may concern:

Be it known that I, William H. Van Gaasbeek, a citizen of the United States, residing at 63 Greenwood Avenue, East Orange, New Jersey, have invented a new, original, and ornamental Design for an Artificial Horizon, of which the following is a specification, reference being had to the accompanying drawing, forming part thereof. In the accompanying drawing:

Fig. 1 is a perspective view of the artificial horizon.

Fig. 2 is a plan view of the artificial horizon.

Fig. 3 is a side view of the artificial horizon.

I claim:

The ornamental design for an artificial horizon, substantially as shown.

WILLIAM H. VAN GAASBEEK.
